UNITED STATES PATENT OFFICE.

ALBERT S. HOWELL, OF CHICAGO, ILLINOIS, ASSIGNOR TO BELL & HOWELL COMPANY, OF CHICAGO, ILLINOIS, A CORPORATION OF ILLINOIS.

AUTOMATIC LIGHT-CONTROL APPARATUS FOR PHOTOGRAPHIC-PRINTING MACHINES.

Application filed July 25, 1921. Serial No. 487,225.

To all whom it may concern:

Be it known that I, ALBERT S. HOWELL, a citizen of the United States, residing at Chicago, in the county of Cook and State of Illinois, have invented a certain new and useful Improvement in Automatic Light-Control Apparatus for Photographic-Printing Machines, of which the following is a full, clear, concise, and exact description, reference being had to the accompanying drawings, forming a part of the specification.

My invention relates to automatic light control apparatus for photographic printing machines especially motion picture film printing machines and relates particularly to such apparatus in which not only does a fed master control element, such as the negative film, control the points during the printing operation when the light changes are made but also controls the degree to which the light is changed as has been heretofore proposed.

The main feature of my invention relates to the provision of mechanism of the above described character which is well adapted to perform its functions under practical conditions and in which the control of the light change apparatus during each light change is effected at one point in the travel of the control member and is not extended over a portion of the feeding movement of the control member whereby the light changes may be made in extremely quick succession.

With this and other features in view my invention consists in certain features of novelty in the construction, combination, and arrangement of parts by which the said features and certain other features herein-after appearing are effected, all as fully described with reference to the accompanying drawings and more particularly pointed out in the claims.

In the said drawings—

Figure 1 is a partial side elevation, partially in section, of a motion picture film printing machine embodying my invention.

Figure 2 is an enlarged section of part of the machine on the line 2—2 of Fig. 1.

Figure 3 is an enlarged view taken on the line 3—3 of Fig. 1.

Figure 4 is a partial section on the line 4—4 of Fig. 3.

Figure 5 is a perspective view of the film advancing member of the machine.

Figure 6 is a partial section on the line 6—6 of Fig. 3.

Figure 7 is a perspective view of certain parts of the adjustable shutter device 60 and related parts partially broken away.

Figure 8 is an enlarged section on the line 8—8 of Fig. 1.

Figure 9 is an enlarged partial section of a portion of the mechanism in elevation 65 similar to Fig. 1.

Figure 10 is a perspective view of a portion of the shutter adjusting mechanism.

Figure 11 is an enlarged section of another portion of the shutter adjusting 70 mechanism.

Figure 12 is a diagrammatical view of the electrical devices of the machine and the circuit connections therebetween.

Figure 13 is a perspective view of a portion of the negative film.

Figure 14 is a reduced section on the line 14—14 of Fig. 2.

Figure 15 is a section on the line 15—15 of Fig. 13.

Like characters of reference indicate like parts in the various views.

In the said drawings 1 designates a standard on the top of which is secured a hollow casing 2 having a cross partition 3 dividing the main enclosure of the casing into front and rear chambers, the front chamber forming a lamp chamber 4 and the rear chamber 5 forming an enclosure for a driving motor 6 which is secured therein. The casing 2 has an extending portion 7 which extends forwardly from the front wall of the lamp chamber and forms an enclosure opening forwardly. The upper wall of the extending portion 7 is formed to provide a square enclosing guide 8 extending in a forward and rearward direction and communicating at its rear end with the lamp chamber 4. Telescoped with this guide for sliding movement in a forward 100

and rearward direction is a square element 9 having an opening therethrough extending from the front to the rear of the same. See Figs. 1 and 2. Secured to the front end 5 of the element 9 in a plane normal to the direction of movement thereof is a film guide plate 10. Disposed in front of the guide plate 10 and hinged to this plate on a vertical axis 11 disposed at one side of 10 the same is a second film guide plate 12. Pivoted to the plate 10 at the opposite side thereof is an arm 13 at the free end of which a headed stud 14 is mounted for axial movement in a forward and rearward direction. 15 when the arm is in operative position, as shown in Fig. 2. When the arm is in this position the head of the stud registers with a depression 15 in the forward face of the plate 12, and the stud is yieldably pressed 20 rearwardly by a compression spring 16 encircling the shank of the stud and abutting the head thereof and a rearwardly facing shoulder formed by an enlargement of the rear portion of the bore in which the stud 25 is mounted. Thus the plate 12 is yieldably pressed toward the plate 10. A knob 17 is secured to the forward end of the shank of the stud 14, which extends forwardly 30 of the arm, so that the stud may be manually withdrawn from the depression 15 and the arm 13 swung away from the plate 12 to permit this plate being swung away from the plate 10. Both plates have rectangular 35 openings 18 therethrough of the size of one picture of a motion picture film and registering with the aforementioned opening of the element 9.

Covering the forward end of the opening 18 of the plate 12 to prevent the passing of 40 actinic light through the opening is a ruby glass 19, it being secured to the forward face of the plate 12 by an annular frame 20 in a usual manner.

A pair of vertical parallel guide ribs 21 45 project from the forward face of the plate 10 and are disposed on opposite sides of the opening 18. These ribs enter respective vertical grooves formed in the rear face of the plate 12 and form side film guides.

The upper wall and the top portions of 50 the side walls of the portion 7 do not extend forwardly as far as the main portions of the side walls and the bottom wall thereof, see Fig. 1, and a vertical plate 22 is secured to the forward edges of the main portion of these side walls and the bottom wall, this plate being disposed just to the rear of the guide plate 10. A plate 23 is mounted for vertical reciprocating movement between the side walls of the portion 55 60 65 7 and between the plate 22 and vertical guide ribs 24 formed on the inner surfaces respectively of these side walls. A horizontal plate 25 is disposed on top of a spacing block 26 which is disposed on top

of the plate 23, and these parts are secured together by means of headed screws 27 passing through vertical holes in the plate 25 and block 26 and screw threaded into the plate 23. See Fig. 3. The plate 25 is disposed below the element 9 and has a pair of horizontally spaced forwardly projecting pins 28 which project through an opening 29 in the plate 10 and perforations of 70 superposed negative and positive films 30 and 31, between the plates 10 and 12 and guide ribs 21, and into a depression 32 in the rearward face of the plate 12 when the film guide comprising plates 10 and 12 is at the rear end of its movement. See Figs. 4 and 5. The pins 28 are disengaged from 75 perforations of the films when the film guide is at the forward end of its movement and the opening 29 and depression 32 are extended vertically to permit movement 80 of the pins from one end of their stroke 85 to the other.

The motor 6 is disposed axially in a forward and rearward direction, and a shaft 35 is journaled in the front wall of the lamp chamber 4 and in the partition 3 in axial alignment with the motor and is driven by the motor in a clockwise direction in Fig. 3 through a friction coupling 36 of usual construction. Secured upon the shaft 35 within the enclosure of the portion 7 of the casing is a cam cylinder 37. Formed on the forward end of this cylinder is a cam 38 which is engaged at diametrically opposite points by a pair of vertically spaced cam rollers 39 rotatably mounted on respective studs 40 secured to the plate 23, whereby the plate 23 is reciprocated vertically when the cam cylinder is rotated. A vertical lever 41 is pivoted at an intermediate point 42, on a horizontal axis normal to the axis of the shaft 35, on an extension 43 extending forwardly from the front wall of the lamp chamber within the enclosure of the portion 7. A cam roller 44 is rotatably mounted on the lower end of this lever and engages a drum cam groove 45 formed in the cam cylinder 37. See Fig. 1. The upper end of the lever 41 extends through an opening 46 in the upper wall of the portion 7 alongside of the guide 8, see Fig. 2, and a stud 47 is secured at the upper end of this lever and extends through a horizontal rearwardly and forwardly extending opening 48 in the guide and engages a laterally extending bore 49 formed in the adjacent side of the element 9. Through this connection the element 9 and the film guide are reciprocated when the cam cylinder 37 is rotated. The cam 38 and cam groove 45 are so formed and timed that when the cam cylinder is rotated in a clockwise direction the film guide is positioned with perforations of the films 30 and 31 in the film guide engaged with the pins 100 105 110 115 120 125 130

28 during the down stroke thereof. When the pins 28 reach the lower end of their stroke the film guide is moved forwardly to disengage the films from the pins and is maintained in this position until the pins have moved into the upper end of their stroke when the film guide is again moved rearwardly to engage the pins with perforations of the film. This action effects a step by step advance of the films.

Pivoted, upon a horizontal axis normal to the movement of the film guide, to a bracket 50 secured to the rear face of the plate 10 is a bell crank lever 51 having one of its legs extending horizontally in a rearward direction from the bracket and having its other leg extending upwardly from the bracket. See Figs. 2 and 6. A headed stud 52 is mounted for sliding movement in a forward and rearward direction in registered bores of the plate 10 and the flange of the element 9 and abuts the rear face of the plate 12 and the forwardly facing side of the upper leg of the bell crank lever with its respective ends whereby when the horizontal leg of the bell crank is moved upwardly the stud 52 is moved forwardly and moves the plate 12 forwardly away from the plate 10 against the influence of the spring 16 acting through the stud 14 as hereinbefore described. The upper wall of the portion 7 has a front wall portion 53 extending downwardly therefrom at the rear of the plate 23 and in front of the lever 41. See Figs. 1 and 3. Pivoted on a stud 54, secured to the wall portion 53 at one side of the cam cylinder on a horizontal forwardly and rearwardly extending axis, and disposed at the rear of the wall portion 53 is a lever 55 which extends over the cam cylinder 37 and has a cam roller 56 mounted at its free end engaging a cam 57 formed on the cam cylinder between the cam 38 and cam groove 45. The lever 55 underlies the horizontal leg of the bell crank lever 51, and when the lever 55 is moved upwardly the bell crank lever is moved thereby to move the stud 53 forwardly whereby the plate 12 is moved forwardly away from the plate 10 as hereinabove described. See Fig. 6. The plate 23 has a vertical slot 58 at the upper end thereof to clear the horizontal leg of the bell crank in all relative positions thereof, and the front wall portion 53 has a relatively large opening 59 through which the said horizontal leg extends. The cam 57 is so formed and timed with relation to the cam 38 and cam groove 45 that the plate 12 is moved toward the plate 10 to clamp the films when the pins 28 are at the lower end of their stroke and is maintained in such position until the pins are re-engaged with perforations of the films at the upper end of their stroke by the rearward movement of the film guide after which the plate 12

is moved forwardly to release the films for movement during the downward stroke of the pins.

The casing 2 has a gear casing 61 extending forwardly at one side of the step by step mechanism hereinabove described and mounted for rotation on this casing and respectively disposed above and below the film guide are film sprockets 62. An extension support 63 is secured to the casing 61 and extends upwardly therefrom, and mounted on this support above the upper sprocket 62 is a pair of film supply spools 64 and 65 which are provided with the usual pivoted retaining arms 66 for holding the film rolls in position on the spools. Supported from the standard 1 is a support 67 extending horizontally below the casing 61, and mounted on this support are film receiving spools 68 and 69 which are provided with the usual pivoted retaining arms 70 for holding the film rolls on the hubs 71 of these spools.

The sprockets 62 are driven in unison, in a counter-clockwise direction in Fig. 1 by a gear train of usual construction, not shown, within the gear casing 61, which gear train is driven with the cam cylinder 37 by a gear 73 secured upon the shaft 35 just in back of the front wall of the lamp chamber 4. The hubs 71 of the film receiving spools 68 and 69 are yieldingly driven, in a clockwise direction in Fig. 1, from the gear train above-mentioned by a belt and pulley mechanism 74 of usual construction. The negative film 30 is fed from the spool 64 over the upper sprocket 62, through the film guide, over the lower sprocket 62 and onto the spool 68. The positive film 31 is fed from the spool 65 over the upper sprocket 62, through the film guide in superposed relation with the negative film over the lower sprocket 62 and onto the spool 69. Idler rollers 75 serve to retain the films on the sprockets 62 and are movable away from respective sprockets 62 in a usual manner to permit convenient threading of the films. The films are looped between the upper and lower sprockets 62 and the film guide to accommodate the step by step of the films through the film guide with the continuous movement thereof over the sprockets.

Secured to the inside surface of the front wall of the lamp chamber 4 and surrounding the opening of the guide 8 is plate member 77 which has a vertical guide way 78 formed on the front surface thereof which cooperates with the inner surface of the said front wall to form a vertical box guide for purposes hereinafter described. See Figs. 1 and 7. The plate member 77 has an aperture 79 formed therein registering with the opening of the guide 8. Secured upon the shaft 35 just in back of the gear 73 is a disk shutter 80 which sweeps by the rear surface of the plate member 77 over the aperture 130

79 thereof. This shutter is of the usual type employed in step printing machines and has the usual opening which permits printing light to be projected into the opening of the element 9 from an incandescent light 81, mounted in the lamp chamber 4 to the rear of the shutter, when the shutter is passing through a portion of its angular movement, and which cuts off the light therefrom when passing through the remainder of its angular movement. This shutter makes one revolution to each cycle of the step by step advancing mechanism hereinabove described, and is so timed that light 15 is permitted to be projected upon the films through the opening of the element 9 and the opening 18 of the plate 10 during each rest period of the movement of the films and is cut off therefrom during advance of the 20 films as is usual.

Mounted for independent vertical movement in the box guide formed by the inner surface of the front wall of the lamp chamber and the guide way 78 of the plate member 77 is a pair of shutter plates 83 which have registerable apertures 84 therein through which light may pass from the aperture 79 into the opening of the element 9. Secured upon the top of the casing 2 is 25 a horizontally disposed frame 85, and journaled for pivotal movement in the ends of this frame and extending in parallelism with the shaft 35 is a rock shaft 86, collars 87 secured to the shaft 86 and abutting the 30 frame 85 providing for end thrust of this shaft. The shutter plates 83 extend upwardly through an opening in the upper wall of the lamp chamber, and the upper ends of these plates have vertically elongated apertures 88 through which the shaft 86 passes. The shaft 86 has a double arm lever 89 secured thereon immediately in back of the shutter plates, and crank studs 90 35 mounted on respective arms of the lever engage respective slots 91 formed at opposite edges of respective shutter plates. See Fig. 7. Each shutter plate is cut away at the edge thereof opposite the slot 91, as designated at 92, to clear the crank stud of the other plate. The crank studs 90 are diametrically opposite with respect to the axis of the shaft 86, and angular movement of the shaft moves the shutter plates in opposite directions. As the shutter plates are moved 40 oppositely by angular movement of the rock shaft the apertures 84 are moved farther or nearer a registering position, which diminishes or increases the light opening through the plates to adjust the amount of light projected upon the films. By reason of the opposite movements of the plates the light opening therethrough is centrally disposed with relation to the light opening 18 of the guide plate 10 in all adjustments of the 45 shutter plates.

The frame element 85 has a horizontal portion 94 disposed some distance above the shaft 86, and this horizontal portion has a plurality of vertical apertures 95 therethrough disposed along the shaft 86. See 70 Fig. 8. Secured in each aperture is a block 96, and each block has a vertical bore 97 therethrough disposed on an axis passing through the shaft 86, and has a slot 98 at its lower end 75 disposed diametrically with relation to the bore 97 and lying in a plane normal to the axis of the shaft 86. A cylindrical element 99 is mounted for longitudinal movement in each bore 97 and has an adjustment plate 100 secured in a diametrical slot at the lower end thereof, see Fig. 10, the adjustment plate being engaged in the slot 98 for vertical movement with the cylindrical element. See 80 Figs. 8, 9, and 10. A pin 101 is secured in a diametrical aperture of the shaft 86 below each adjustment plate 100 and extends outwardly on opposite sides of the shaft. Each adjustment plate 100 has an intermediate slot 102 cut in its lower edge directly over the shaft so that it can be moved to the lower end of its stroke without abutting the shaft, and when each adjustment is moved downwardly 85 the lower edge surfaces of the plate lying on opposite sides of the slot 102 thereof move against opposite ends of the respective pin 101 and in such movement angularly move the shaft 86 in either direction to a predetermined position which is effected when both lower edge surfaces of the plate abut 90 respective ends of the respective pin 101. The pins 101 are disposed in different angular positions on the shaft 86 so that downward movement of respective adjustment plates effects respective individual angular 95 positions of the shaft. In Fig. 11 one pin 101 is shown in full lines and different angular positions of other of these pins are shown in dotted lines. As hereinabove described angular movement of the shaft 86 effects 100 adjustment of the adjustable shutter device comprising the shutter plates 83, and accordingly when the shaft 86 is angularly positioned by downward movement of an adjustment plate 100 the shutter plates are correspondingly adjusted. Thus individual actuation of each adjustment device, hereinabove described, effects variance of the light to a predetermined degree.

Secured on each block 96 above the horizontal portion 94 of the frame 85 and in concentric relation with the bore 97 thereof is an open cored electro-magnet 104, and mounted for sliding movement in the core of each electro-magnet is a cylindrical armature piece 105 of suitable metal, the lower end of each of which is reduced and screw threaded into the upper end of the respective cylindrical element 99. See Fig. 8. A coiled compression spring 106 encircles the 105 110 115 120 125 130

reduced lower end of each armature piece and abuts the downwardly facing shoulder thereof formed by the reduced lower end of the armature piece and the upper end of the block 96 with its opposite ends, and serves to return the armature piece, cylindrical element 99, and adjustment plate 100 to the upper end of their stroke and to maintain them there normally. Energization of each 10 electro-magnet attracts the respective armature piece 105 downwardly and moves the respective adjustment plate 100 downwardly to cooperate with the respective pin 101 to position the shaft 86 angularly as hereinabove described.

Journaled for pivotal movement in the ends of the frame 85 in parallelism to the shaft 86 and disposed above the same and to one side of the blocks 96 is a second rock 20 shaft 107, collars 108 being secured to the shaft 107 and abutting the frame 85 providing for end thrust of this shaft. A latch lever 109 is secured to the shaft 107 in a plane to one side and immediately adjacent 25 each adjustment plate 100. Each latch lever has a lateral lug 110 at the free end thereof extending toward the respective cylindrical element 99, and the upper edge 111 of each lug is inclined downwardly and outwardly from the main portion of the lever to form a cam surface, and the lower edge 112 is inclined oppositely to form a lock surface. Each adjustment plate is provided 30 with a laterally extending lug 113 lying in the plane of the respective latch lever and disposed on the side thereof from which the lug 110 projects to cooperate with the lug 110 of the respective latch lever. A lever 114 is secured to the shaft 107 adjacent the rear end thereof and extends downwardly from the shaft. A tension spring 115 has one end secured to the lower end of the lever 114 and has its other end secured 40 to a stud 116 mounted in the end wall of the frame 85. This spring tends to move the shaft 107 in a clockwise direction in Fig. 8 to maintain the latch levers against the lugs 113. When the adjustment plates 45 100 are in their normal upper position the lugs 113 thereof are disposed above the lugs 110 of respective latch levers 109, and when any adjustment plate is moved downwardly its lug 113 bears against the upper edge 111 of the respective lug 110 and moves all the 50 latch levers, against the influence of spring 115, outwardly away from their normal positions. The lug 113 of the downwardly moving adjustment plate then rides over the end of the respective lug 110 and below the same, after which the spring 115 moves the 55 latch levers back to normal position and the lower edge 112 of the respective lug engages the lug 113 of the downwardly moving adjustment plate from above and locks this adjustment plate agains the respective pin

101 of the shaft 86 and thus prevents the respective spring 106 from moving this adjustment plate upwardly to normal position. Thus the shaft 86 is automatically locked in each adjusted position and the adjustable 70 shutter device is prevented from moving out of adjusted position as the machine is operated. In Figs. 8 and 9 are shown adjustment plates in opposite ends of their strokes. When a second adjustment plate is 75 moved downwardly its lug 113 actuates the latch levers in a similar manner, and as the latch levers are moved against the influence of the spring 115 the previously locked adjustment plate is released and the respective 80 spring 106 moves it upwardly to its normal position, the shaft 86 being re-adjusted by the downward movement of the second adjustment plate. This action is repeated with the downward movement of each adjustment plate.

Secured on the side of the guide 8 at the front end thereof is a circuit breaker box 118 forming an enclosure. See Figs. 1, 2, and 14. Within the enclosure of this box intermediate the front and rear ends thereof is secured a vertically disposed block 119 of nonconducting material in which is permanently embedded a plurality of vertically spaced pairs of wires 120 extending forwardly and rearwardly therefrom, and the wires of each pair of which are horizontally spaced. These wires are formed of spark 90 resisting spring metal, such as tungsten, and extend forwardly and rearwardly of the 100 block 119. The front ends of the wires of each pair are turned toward each other, as designated at 121, and are normally spaced from each other so that when the front end of one wire is flexed toward its mate a contact is formed and so that when the one wire is released it will spring back to normal position to break the contact. Individually pivoted on a common vertical shaft 122, secured to and extending between the upper 110 and lower walls of the circuit breaker box at the front end thereof, is a plurality of vertically spaced bell crank levers 123. These bell crank levers are disposed in the horizontal plane of respective pairs of wires 115 120, and one leg of each extends rearwardly on the side of the respective pair of wires opposite that on which the guide 8 lies. The other leg of each bell crank lever extends in a direction toward the guide 8 at right 120 angles to the other leg thereof and has a rearwardly facing engaging surface 124 at its free end. When any of these bell crank levers is moved in a counter-clockwise direction in Fig. 2 the one wire of the respective 125 pair is moved into contact with its mate. The normal tendency of each wire 120 engaged with respective bell crank levers is to move the respective bell crank lever in a clockwise direction in Fig. 2 against the outer wall of 130

the box 118 which forms a stop therefor. Secured to the rear face of the plate 10 on the same side of the element 9 as the box 118 is disposed is a block 126 extending in a forward and rearward direction and having an opening 127 extending therethrough in a forward and rearward direction. The front end of the block 126 extends through an aperture 128 in the plate 10 at one side of the films in the guide and into a recess 129 formed in the rear surface of the plate 12. Secured to and extending between the upper and lower walls of the block 126 at the extreme front end thereof is a vertically disposed shaft 131, and a plurality of vertically spaced levers 132 are individually pivoted on the shaft 131. These levers are disposed in the same horizontal planes as respective bell crank levers 123, and extend rearwardly of the shaft 131 through the opening 127 to points alongside of respective bell crank levers. The rear ends of the levers 132 have forwardly facing engaging surfaces 133 adapted to engage surfaces 124 of respective bell crank levers 123. A plurality of springs 134 are secured to the outer wall of the block 126 and engage respective levers 132 to move and normally maintain them against the inner wall of the block which serves as a stop therefor. When positioned against the inner wall of the block 126 the surfaces 133 of these levers are out of position to engage the surfaces 124 of respective bell crank levers, and when the levers 132 are moved outwardly from their normal positions they are moved into position to engage the surfaces 124 of respective bell crank levers. As will be noted the levers 132 reciprocate forwardly and rearwardly with the element 9 and the film guide as moved by the cam groove 45 when the cam cylinder 37 is rotated in the operation of the machine. When any one of these levers 132 is positioned outwardly of its normal position forward movement of the element 9 and a film guide from their rear positions will cause the surface 133 of this lever to engage the surface 124 of the respective bell crank lever and through this connection will pivotally move the bell crank lever in a counter-clockwise direction in Fig. 2 and contact the respective pair of wires 120. The levers 132 are shown in both positions of their movement in Fig. 2.

55 The hereinbefore-mentioned opening 128 in the plate 10 extends to the light opening 18 therein, and the levers 132 have lateral extensions 135 extending toward the light opening. The ends of these extensions have forwardly facing contact surfaces 136 disposed along the path of movement of the films over the marginal portion of the outer surface of the negative film in the film guide between the adjacent edge of the film and the perforations adjacent thereto. These

contact surfaces lie in the plane of the film face engaging surface of the plate 10 when the levers 132 are in normal position.

Irregularities 137, see Figs. 13 and 15, formed by displacing small-circular portions of the negative film, which is employed as a control member, out of the normal plane of the film in a direction away from the positive film without breaking or cutting the film, are disposed in predeterminedly selected arrangement along the aforementioned marginal portion of the negative film. These irregularities are disposed both with relation to the selection of certain levers 132 and with relation to the particular rest period in the movement of the films during which the irregularities are to register with the contacting surfaces 136 of respective levers 132, and operate to move respective levers 132 out of normal position into position to engage the surfaces 133 of these levers with the surfaces 124 of the respective bell-crank levers 123 in a manner now to be described.

As herein above described the films are advanced step by step through the film guide and the plate 12 is positioned away from the plate 10 during each advance of the films to permit free movement of the films and is positioned adjacent the plate 10 to maintain the films in close superposed relation during each rest period during which the printing of the positive film is effected. The irregularities 137 are disposed to register with respective contact surfaces 136 during the respective rest periods. After the films come to rest and immediately after the film guide has been moved rearwardly sufficiently so that the surfaces 133 of the levers 132 lie to the rear of the surfaces 124 of the bell crank levers 123 the plate 12 is moved toward the plate 10 and the irregularities 137 registering with respective contact surfaces 136 are projected rearwardly against respective contact surfaces 136 and move the respective levers 132 out of normal position into position to engage surfaces 133 of these levers with surfaces 124 of respective bell crank levers 123 as hereinbefore described. The plate 12 is maintained in its position adjacent the plate 10 until after the element 9 is moved forwardly which movement, as hereinbefore described, effects the closing of the selected circuit breakers through the engagement of surfaces 133 of the levers 132 with the surfaces 124 of respective bell crank levers 123. After this action takes place the plate 12 is moved away from the plate 10 thereby releasing the irregularities from respective contact surfaces 135, and the films are then advanced, the springs 134 returning the levers 132 after the pressure between the surfaces 133 thereof and the surfaces 124 of respective bell crank levers has been re-

leased by rearward movement of the element 9 and the film guide. The film face engaging surface of the plate 10 has a vertical groove 138 extending through the length thereof in line with the path of the irregularities 137 so that the irregularities pass through the film guide without interference and so that they do not interfere with movement of the plate 12 toward the plate 10. It will be noted that this mechanism operates in a very positive manner and that the irregularities are not subjected to undue wear or rubbing in the operation of the machine.

It will be noted that the irregularities 137 are formed without breaking or cutting the film and that they may be pressed back into the normal plane of the film whereby corrections may be easily made in the disposition of the irregularities.

The energization of electro-magnets 104 is selectively controlled by the circuit breaker devices comprising the pairs of wires 120, hereinabove described, which circuit breakers are preferably less in number than the number of electro-magnets. This selective control of the energization by a relatively small number of circuit breakers is effected in the following manner. The number of electro-magnets, and likewise the number of adjustment devices, is divisible by a divisor which when added to the quotient of such division gives a number less than the number of electro-magnets. In the drawings twenty electro-magnets are shown and a divisor of this number and the quotient of such division are respectively four and five, which when added together gives nine. Accordingly there are nine pairs of wires 120, nine bell crank levers 123, and nine levers 132. Referring to Fig. 12 the circuit connections relating the circuit breakers with the electro-magnets are as follows. One pole of a source of electricity is connected by a circuit connection 139 with one wire 120 of each of five of the pairs thereof. One wire of each of the remaining four pairs of wires 120 is connected by a circuit connection 140 with the other pole of the source of electricity. The other wires of each pair of the first mentioned group of pairs of wires 120 are each connected by respective branch circuit connections 141, 142, 143, 144, and 145 to one terminal of a respective group of five electro-magnets 104, and the other wires of each pair of the second mentioned group of pairs of wires 120 are each connected by respective branch circuit connections 146, 147, 148, and 149 to the other terminals of respective groups of four electro-magnets which latter groups of electro-magnets are each composed of one electro-magnet of each of the first mentioned groups thereof. This wiring arrangement connects each electro-magnet 104 in series with a different pair of circuit breakers thus

effecting a selective control thereof. Due to this arrangement two circuit breakers must be closed at the same time and the irregularities 137 are arranged in pairs to effect simultaneous movement of respective levers 132 out of normal position and to thereby effect simultaneous movement of respective circuit breakers out of their normal open position to closed position. The circuit connections between the circuit breakers and electro-magnets include detachable circuit connector devices 150 mounted on blocks 151 of insulating material mounted on top of the casing 2 below the horizontal portion 94 of the frame 85, see Figs. 8 and 9, and a detachable cover 152 is fitted over the frame 85 and parts related therewith. A sheet of mica 153 is placed between each pair of wires 120 to prevent contact of the wires of different pairs.

It will be noted that each light change is controlled at one point in the travel of the films and is not extending over a portion of the feeding movement of the film so that light changes from any one degree to any other may be effected in extremely quick succession. And it will be noted further that a succession of operations of the light varying mechanism is not necessary to effect any desired light change.

While I have herein shown and particularly described the preferred embodiment of my invention I do not wish to be limited to the precise details of construction shown as changes may readily be made without departing from the spirit of my invention, but having thus described my invention I claim as new and desire to secure by Letters Patent the following:

1. A photographic printing machine including feeding means operating constantly during the printing operation, a control member fed by said feeding means and having irregularities disposed in predeterminedly selected arrangement thereon, a source of printing light, means for varying the printing light to predetermined degrees including a plurality of separately actuatable adjustment devices, a plurality of electro-magnets for controlling actuation of respective adjustment devices, a plurality of circuit breaker devices, circuit connections whereby said electro-magnets are selectively controlled by said circuit breaker devices, said circuit breaker devices being normally in position to prevent actuation of said adjustment devices and individually controlled, to be caused to move into and out of position to effect actuation of said adjustment devices, by respective irregularities of the control member when it is in respective positions of its travel.

2. A photographic printing machine including means for feeding superposed negative and positive films, the negative film hav-

ing irregularities disposed in predeterminately selected arrangement thereon, means for projecting printing light upon a section of the path of the superposed films, means 5 for varying the light to predetermined degrees including a plurality of separately actuatable adjustment devices, a plurality of electro-magnetic devices for controlling actuation of respective adjustment devices, a 10 plurality of circuit breaker devices, and circuit connections whereby individual energization of said electro-magnetic devices is selectively controlled by said circuit breaker devices, said circuit breaker devices being 15 normally in position to prevent actuation of said adjustment devices and individually controlled, to be caused to move into and out of position to effect actuation of said adjustment devices, by respective irregularities of the negative film when it is in 20 respective positions of its travel.

3. A photographic printing machine including feeding means operating to feed at a regular rate during the printing operation, a control member fed thereby and having irregularities disposed in predeterminately selected arrangement thereon, a source of printing light, means for varying the printing light to predetermined degrees including a plurality of separately actuatable adjustment devices of a divisible number having a divisor, which when added to the quotient of such division gives a number less than the number of adjustment devices, 30 a plurality of electro-magnetic devices equal in number to the number of adjustment devices adapted when energized to effect actuation of respective adjustment devices, a plurality of circuit breaker devices 35 equal in number to the sum of said divisor and quotient and normally in open position and individually controlled, to be caused to move into and out of closed position, by respective irregularities of the control member when it is in respective positions of its travel, and circuit connections connecting each electro-magnetic device in series with a different pair of circuit breaker devices.

4. A photographic printing machine including means for feeding superposed negative and positive films in printing relation, the negative film having irregularities disposed in predeterminately selected arrangement thereon, means for projecting printing 50 light upon a section of the path of the superposed films, means for varying the printing light to a plurality of predetermined degrees including a plurality of separately actuatable adjustment devices of a divisible number having a divisor which when added to the quotient of such division gives a number less than the number of adjustment devices, a plurality of electro-magnets equal 55 in number to the number of adjustment devices adapted when energized to effect actuation 60

of respective adjustment devices, a plurality of circuit breaker devices equal in number to the sum of said divisor and quotient and normally in open position and individually controlled, to be caused to move 70 into and out of closed position, by respective irregularities of the negative film when it is in respective positions of its travel, and circuit connections connecting each electro-magnetic device in series with a different 75 pair of circuit breaker devices.

5. A photographic printing machine including a film guide having a light opening therein, a negative film having irregularities disposed in predeterminately selected 80 arrangement thereon corresponding with differences in densities of the same, means for feeding the negative film and a positive film in superposed printing relation therewith through said film guide, means for 85 varying the light projected into said opening to a plurality of predetermined degrees including a plurality of separately actuatable adjustment devices of a divisible number having a divisor which when added to the 90 quotient of such division gives a number less than the number of adjustment devices, a plurality of electro-magnetic devices equal in number to the number of adjustment devices adapted when energized to effect actuation of respective adjustment devices, a 95 plurality of circuit breaker devices equal in number to the sum of said divisor and quotient and normally in open position and individually controlled, to be caused to move into and out of closed position, by respective irregularities of the negative film when it is in respective positions of its travel, and circuit connections connecting each electro-magnetic device with a different 100 pair of circuit breaker devices.

6. A photographic printing machine including feeding means, a source of light, means for varying the light to predetermined degrees including a plurality of separately reciprocable adjustment elements, means for individually reciprocating said adjustment elements including a plurality of electro-magnetic devices, a plurality of circuit breakers individually controlled by a 110 control member fed by said feeding means, and circuit connections whereby said electro-magnetic devices are selectively controlled by said circuit breaker devices.

7. A photographic printing machine including feeding means operating constantly during the printing operation, a source of printing light, a control member fed by said feeding means and having irregularities disposed in predeterminately selected arrangement thereon, means for varying the light to predetermined degrees including a plurality of adjustment elements yieldably pressed into one end of their strokes, a plurality of electro-magnets for moving 120 125 respectively the adjustment elements, and circuit connections connecting each electro-magnet with a different pair of circuit breaker devices.

5 tive adjustment elements to the opposite ends of their strokes, a plurality of circuit breakers normally open and individually controlled, to be moved into and out of closed position, by respective irregularities of the control member when it is in respective positions of its travel, and circuit connections whereby said electro-magnets are selectively energized by closure of respective 10 circuit breakers.

8. A photographic printing machine including a film guide having a light opening therein, a negative film having irregularities disposed in predeterminately selected arrangement thereon, means for feeding said negative film and a positive film in superposed relation therewith through said film guide, means for varying the light to predetermined degrees including a plurality of 15 separately reciprocable adjustment elements, a plurality of electro-magnetic devices for controlling actuation of respective adjustment elements, a plurality of circuit breakers individually controlled by respective irregularities of the negative film when it is in respective positions of its travel, and circuit connections whereby said electro-magnetic devices are selectively controlled by said circuit breakers.

30 9. A photographic printing machine including feeding means, a source of printing light, means for varying the light to predetermined degrees including a plurality of separately reciprocable adjustment elements 35 yieldably pressed into one end of their strokes, means under the control of a control member fed by said feeding means for effecting intermittently individual actuation of said adjustment elements to the opposite end 40 of their strokes, and releasable latch means for automatically locking any adjustment element at said opposite end of its stroke and operated by the movement of any adjustment element toward said opposite end of its stroke to release a previously locked adjustment element.

45 10. A photographic printing machine including feeding means operating constantly during the printing operation, a control member fed thereby and having irregularities disposed in predeterminately selected arrangement thereon, a source of light, means for varying the light to predetermined degrees including a plurality of separately reciprocable adjustment elements yieldably pressed into one end of their strokes, a plurality of electro-magnetic devices for moving respective adjustment elements to the opposite end of their strokes, a plurality of 50 circuit breaker devices normally open and individually controlled, to be moved into and out of closed position, by respective irregularities of the control member when it is in respective positions of its travel, and 55 releasable latch means for automatically

locking any adjustment element at said opposite end of its stroke and operated by the movement of any adjustment element toward said opposite end of its stroke to release a previously locked adjustment element. 70

11. A photographic printing machine including means for feeding superposed negative and positive films, the negative film having irregularities disposed in predeterminately selected arrangement thereon, means for projecting printing light upon a section of the path of the superposed films, means for varying the light to predetermined degrees including a plurality of separately reciprocable adjustment elements yieldably pressed into one end of their strokes, means for effecting actuation of said adjustment elements including a plurality of control devices selectively controlling individual actuation of said adjustment elements to the opposite end of their strokes and individually controlled, to effect intermittent actuation of said adjustment elements, by respective irregularities of the negative film 90 when it is in respective positions of its travel, and releasable latch means for automatically locking any adjustment element at said opposite end of its stroke and operated by the movement of any adjustment element toward said opposite end of its stroke to release a previously locked adjustment element. 95

12. A photographic printing machine including feeding means operating constantly 100 during the printing operation, a source of printing light, an adjustable shutter device, means for adjusting said device to predetermined degrees including a plurality of separately reciprocable adjustment elements 105 and a pivoted device operatively connected with said shutter device and adapted to be angularly moved to individual predetermined positions by movement of respective adjustment elements to one end of their strokes, and means under the control of a control member fed by said feeding means for effecting intermittently individual actuation of said adjustment elements to said 110 one end of their strokes. 115

13. A photographic printing machine including feeding means, a control member fed by said feeding means and having irregularities disposed in predeterminately selected arrangement thereon, a source of 120 printing light, means for varying the light to predetermined degrees including a plurality of separately reciprocable adjustment elements and a pivoted device adapted to be angularly moved to individual predetermined positions by movement of respective adjustment elements to one end of their strokes, a plurality of electro-magnets for moving respective adjustment elements to 125 said one end of their strokes, a plurality of 130

circuit breakers normally open and individually controlled, to be moved into and out of closed position, by respective irregularities of the control member when it is in respective positions of its travel, and circuit connections whereby said electromagnets are selectively controlled by said circuit breakers.

14. A photographic printing machine including a film guide having a light opening therein, means for feeding superposed positive and negative films through said guide, means for varying the light to predetermined degrees including a plurality of separately reciprocable adjustment elements yieldably pressed to one end of their strokes and a pivoted device adapted to be angularly moved to individual predetermined positions by movement of respective adjustment devices to the opposite end of their strokes, releasable latch means adapted to lock automatically any adjustment element at said opposite end of its stroke and operated by the movement of any adjustment element toward said opposite end of its stroke to release a previously locked adjustment device, and means under the control of one of said films for effecting intermittently individual actuation of said adjustment elements to said opposite end of their strokes.

15. A photographic printing machine including feeding means, a source of printing light, a control member fed thereby and having irregularities disposed in predeterminedly selected arrangement thereon, means for varying the light to predetermined degrees including a plurality of separately reciprocable adjustment elements yieldably pressed into one end of their strokes and a pivoted device adapted to be angularly moved to individual predetermined positions by movement of respective adjustment elements to the opposite end of their strokes, releasable latch means adapted to lock automatically any adjustment element at said opposite end of its stroke and operated by the movement of any adjustment element toward said opposite end of its stroke to release a previously locked adjustment element, and means for effecting actuation of said adjustment elements to said opposite end of their strokes including a plurality of devices selectively controlling individual movement of said adjustment elements to said opposite end of their strokes and individually controlled, to effect intermittent actuation of said adjustment elements to said opposite end of their strokes, by respective irregularities of the control member when it is in respective positions of its travel.

16. A photographic printing machine including step by step feeding means adapted to feed a control member having an ir-

regularity thereon, an element adapted to register with said irregularity during a predetermined rest period in the feeding movement of the control member and adapted to be caused to assume abnormal relation 70 with the control member by the registering irregularity when said element and the control member are relatively moved toward each other laterally of the feeding movement of the control member, and means operating in timed relation with said feeding means and adapted to yieldingly effect relative movement of said element and control member toward each other laterally of the feeding movement of the control member and to effect relative movement of the same away from each other during each rest period in the feeding movement of the control member.

17. A photographic printing machine including step by step feeding means, control member fed thereby and having an irregularity thereon, a support, an element movably mounted thereon for movement to and away from the control member laterally of the feeding movement of the control member and yieldably pressed into a position adjacent the control member, said element being adapted to register with said irregularity when the control member is in 90 a predetermined rest period in the feeding movement thereof and adapted to be caused by said irregularity when registering therewith to assume an abnormal relation with the control member when said support and control member are relatively moved toward each other laterally of the feeding movement of the control member, and means operating in timed relation with said feeding means and adapted to relatively move 100 said support and control member to and away from each other laterally of the feeding movement of the control member during each rest period in the feeding movement of the control member.

18. A photographic printing machine including step by step feeding means adapted to feed a control member having a laterally projecting irregularity disposed in predeterminedly selected position thereon, means operating in timed relation with said feeding means adapted to position the control member laterally of the feeding movement thereof in the direction in which said irregularities project and to release the same 110 from such position during each rest period of the feeding means, and a movable element yieldably pressed into a normal position and adapted to be moved out of normal position by the irregularity of the control 120 member when registering therewith when said second mentioned means laterally positions the control member.

19. A photographic printing machine including a guide comprising opposing face 130

- guide plates disposed opposite respective faces of a strip guided thereby, one of said guide plates being movable to and away from the other guide plate, step by step feeding means adapted to feed a strip through said guide, said strip having an irregularity projecting laterally from a face thereof at a predeterminately selected point thereon, means operating in timed relation with said feeding means adapted to move said movable guide plate toward and away from the other guide plate during each rest period in the feeding of the strip, and a pivoted lever yieldably pressed into one end of its movement and adapted to be moved out of the aforementioned end of its movement by said irregularity registering therewith when said movable guide plate is moved toward the other guide plate.
20. A photographic printing machine including step by step feeding means, a control member fed thereby and having irregularities disposed thereon in predeterminately selected arrangement thereon, a support, a plurality of elements mounted on said support for individual movement laterally of the feeding movement of the control member and yieldably pressed to the end of their movement adjacent the control member, said elements being adapted to register with respective irregularities of the control member during respective rest periods in its feeding movement and adapted to be caused individually to assume abnormal relation with the control member by respective registering irregularities when said support and control member are relatively moved toward each other during respective rest periods in the feeding movement of the control member, and means operating in timed relation with said feeding means adapted to relatively move said support and control member towards each other and to release during each rest period in the feeding movement of the control member.
21. A photographic printing machine including step by step feeding means adapted to feed a control member having laterally projecting irregularities disposed in predeterminately selected arrangement thereon, a support, a plurality of levers pivotally mounted on said support for individual movement laterally of the feeding movement of the control member and yieldably pressed to the end of their movement adjacent the control member, said levers being adapted to register with respective irregularities of the control member during respective rest periods in its feeding movement and adapted to be individually moved out of said aforementioned end of their movement by respective registering irregularities when said support and control member are relatively moved toward each other during respective rest periods in the feeding movement of the control member, and means operating in timed relation with said feeding means adapted to move said movable guide plate toward the other guide plate during each rest period in the feeding movement of the strip, and a pivoted lever yieldably pressed into one end of its movement and adapted to be moved out of the aforementioned end of its movement by said irregularity registering therewith when said movable guide plate is moved toward the other guide plate, and a circuit breaker device normally in one position and adapted to be moved to the opposite position thereof.
22. A photographic printing machine including a film guide comprising opposing face guide plates disposed opposite respective faces of a film guided thereby, one of said guide plates being movable to and away from the other guide plate, step by step feeding means adapted to feed a film through said guide, said film having irregularities projecting laterally from a face thereof and disposed in predeterminately selected arrangement thereon, means operating in timed relation with said feeding means and adapted to move said movable guide plate toward and away from the other guide plate during each rest period in the feeding movement of the film, and a plurality of elements mounted for individual movement and yieldably pressed to one end of their movement, said elements being adapted to register with respective irregularities during respective rest periods in the feeding of the film and adapted to be moved individually out of the aforementioned end of their strokes by respective registering irregularities when said movable guide plate is moved toward the other guide plate.
23. A photographic printing machine including a reciprocable guide comprising opposing face guide plates, one of which is movable to and away from the other plate, a perforation engaging advancing member reciprocable in a plane normal to the plane of reciprocation of the guide, means for reciprocating said guide and said advancing member in timed relation to effect step by step advance of perforated strip in said guide, said strip having an irregularity projecting from a face thereof and disposed in a predeterminately selected position thereon, means operating in timed relation with said means adapted to move said movable guide plate toward the other guide plate before and to move the same away from said other guide plate after one stroke of the reciprocation of the guide during each rest period in the feeding movement of the strip, a device mounted to reciprocate with the guide and movably mounted with respect thereto and yieldably pressed into one end of its movement, said device being adapted to be moved out of a normal position by said irregularity registering therewith when said movable guide plate is moved toward the other guide plate, and a circuit breaker device normally in one position and adapted to be moved to the opposite position thereof.

by said device when it is out of normal position during an aforementioned stroke of the guide.

24. A photographic printing machine including a reciprocable guide comprising opposing guide plates, one of which is movable to and away from the other plate, a perforation engaging advancing member reciprocable in a plane normal to the plane of reciprocation of the guide, means for reciprocating said guide and advancing member in timed relation to effect step by step advance of a perforated strip in said guide, said strip having irregularities disposed in predeterminedly selected arrangement thereon, means operating in timed relation with said means adapted to move said movable guide plate toward the other guide plate before and to move the same away from said other guide plate after one stroke of the reciprocation of the guide during each rest period in the feeding movement of the strip, a plurality of devices mounted to reciprocate with the guide and individually movable with respect thereto and yieldably pressed into one end of their movement, each device being adapted to assume an abnormal relation with the strip when a respective irregularity of the strip registers therewith during movement of said movable guide plate toward the other guide plate, and a plurality of circuit breaker devices yieldably pressed into one position and adapted to be moved individually to the opposite position thereof by respective devices in said abnormal relation during respective aforementioned strokes of the guide.

25. A photographic printing machine including a perforated strip having laterally projecting irregularities projecting from a face thereof and disposed in predeterminedly selected arrangement thereon, a guide reciprocable in a path normal to the faces of the strip and comprising opposed guide plates disposed opposite respective faces of the strip, one of said guide plates being movable to and away from the other plate, a perforation engaging advancing member reciprocable in a plane normal to the plane of reciprocation of the guide, means for reciprocating said guide and advancing member in their respective planes of movement and in timed relation to effect step by step advance of the strip, means operating in timed relation with said means adapted to move said movable guide plate toward the other guide plate before and to move the same away from said other guide plate after one stroke of the reciprocation of the guide during each rest period in the feeding movement of the strip, a plurality of devices

mounted to reciprocate with the guide and individually movable with respect thereto and yieldably pressed into one end of their movement, each device being adapted to be moved out of said end of its movement by a respective registering irregularity of the strip during movement of said movable guide plate toward the other guide plate, and a plurality of circuit breaker devices yieldably pressed into open position and adapted to be individually moved to closed position by respective devices out of normal position during respective aforementioned strokes of said guide.

26. A photographic printing machine including a film guide comprising opposing face guide plates lying opposite respective outer faces of perforated superposed positive and negative films and one of said plates having a light opening therein, the negative film lying next to the guide plate having the light opening therein and having laterally projecting irregularities arranged in predeterminedly selected order along the same at the side of the light opening and projecting toward the guide plate having the light opening, said guide being reciprocable in a path normal to the faces of the films and one of said guide plates being movable to and away from the other guide plate, a perforation engaging advancing member reciprocable in a plane normal to the plane of reciprocation of the guide, means for reciprocating said guide and advancing member in their respective planes of movement and in timed relation to effect step by step advance of the films, means operating in timed relation with said means adapted to move said movable guide plate toward the other guide plate before and to move the same away from said other guide plate after one stroke of the reciprocation of the guide during each rest period in the feeding movement of the films, a plurality of devices mounted to reciprocate with the guide and individually movable with respect thereto and yieldably pressed into one end of their movement, each device being adapted to be moved out of said end of its movement by a respective registering irregularity of the negative film during movement of said movable guide plate toward the other guide plate, and a plurality of circuit breaker devices yieldably pressed into open position and adapted to be individually closed by respective devices out of normal position during respective aforementioned strokes of said guide.

In witness whereof I hereunto affix my signature this 22nd day of July, 1921, A. D.

ALBERT S. HOWELL.
